(57) **CLAIM**

The ornamental design for a three-dimensional printed home, as shown and described.

DESCRIPTION

FIG. 1 is a front prospective view of the three-dimensional printer home, showing the new design;

FIG. 2 is a rear perspective view thereof;

FIG. 3 is a reduced front elevational view thereof; the rear elevational view being a mirror image thereof;

FIG. 4 is a reduced top plan view thereof; the bottom plan view being a mirror image thereof;

FIG. 5 is reduced left side elevational view thereof; and, FIG. 6 is a reduced right-side elevational view thereof.

The broken lines are for the purpose of illustrating portions of the three-dimensional printed home that form no part of the claimed design.

The appearance of any portion of the three-dimensional printed home between the break lines shown in FIGS. 1-6 forms no part of the claimed design.
